UNITED STATES PATENT OFFICE.

ALBIN WARTH, OF STAPLETON, NEW YORK.

LUBRICATOR.

SPECIFICATION forming part of Letters Patent No. 372,997, dated November 8, 1887.

Application filed March 3, 1887. Serial No. 229,562. (No model.)

To all whom it may concern:

Be it known that I, ALBIN WARTH, a citizen of the United States, residing at Stapleton, in the county of Richmond and State of New York, have invented new and useful Improvements in Lubricators, of which the following is a specification.

This invention relates to a lubricator which can be adjusted so as to deliver any desired quantity of oil, and which is provided with an alarm to indicate automatically when all the oil is discharged from the measuring-chamber.

The invention consists of certain new combinations of parts, as fully pointed out in the following specification and claims, and illustrated in the accompanying drawings, in which—

Figure 1 represents a horizontal section in the plane $x'x$, Fig. 3. Fig. 2 is a transverse vertical section in the plane $y'y$, Fig. 1. Fig. 3 is a longitudinal vertical section in the plane $z'z$, Fig. 1. Fig. 4 is a detached side elevation of the plunger and barrel for measuring and delivering the oil, on a larger scale than the previous figures. Fig. 5 is a transverse section in the plane $x'x'$, Fig. 4. Fig. 6 is a transverse section in the plane $y'y'$, Fig. 3. Fig. 7 is a transverse section in the plane $z'z'$, Fig. 3. Figs. 8 to 14 are details, which will be referred to as the description progresses. Fig. 15 is a longitudinal section of a modification.

Similar letters indicate corresponding parts.

In the drawings, the letter A designates the oil-cistern, which is open at the bottom and communicates freely with the supply-chamber B. This supply-chamber is provided at one end with a rigid head, a, while its opposite end is open and provided with a movable head, C, which, however, is firmly clamped between the supply-chamber and the barrel D by means of screws b b, Fig. 1. On the rigid head a of the chamber B is formed a stuffing-box, c, and through this stuffing-box extends a rod, E, on which is secured a cross-head, F, which connects with the driving-shaft G, Fig. 1, so that by turning said shaft a reciprocating motion is imparted to the rod E.

In the example shown in the drawings the driving-shaft G carries two eccentrics, d d, which connect by rods e e with the cross-head

F; but I do not wish to confine myself to these precise means for imparting to the rod E a reciprocating motion. From the cross-head F rises a standard, f, provided with an eye which fits a stud, g, firmly secured in the rigid head of the supply-chamber B, so that the cross-head F is effectually prevented from turning round, while it is free to move in the direction of the axis of the rod E. On the casting which composes the cross-head F and the standard f is formed a disk, G', Figs. 1, 3, and 7, which is provided with a series of holes, g^2 g^{21} g^{22} g^{23} g^{24} g^{25} g^{26} g^{27} , and on the outer end of the rod E is fitted a sleeve, H, which carries the index I. The sleeve H is fitted upon the rod E by means of a feather-key, h, and the index I is exposed to the action of a spring, i, which has a tendency to force the point of said index toward the disk G'. The casting which forms the cross-head F, the standard f, and the disk G' abuts against a shoulder, j, formed on the rod E, Fig. 3, and on the outer end of this rod is cut a screw-thread to fit a nut, J, which serves to act upon the sleeve H. When this nut is turned back, the sleeve, together with the rod E, can be turned until the point of the index engages one of the holes—for instance, g^{26} in the disk G'—and when the nut J is then screwed up the rod E is firmly connected to the cross-head F, so that it cannot turn round, and is compelled to partake of the movements of the cross-head.

The devices for graduating the quantity of oil delivered for each stroke of the mechanism consist, principally, of a measuring-chamber, a plunger working in this measuring-chamber, relief-openings, through which the surplus oil flows back from the measuring-chamber into the supply-chamber, and a relief-regulator.

In the example shown in Fig. 3 of the drawings the relief-regulator is made in the form of a shell, L, which is ground upon a tapering plug, M, projecting from the movable head C of the supply-chamber B. A pin, k, which projects from this relief-regulator, engages an arm, K, which is secured on the inner end of the rod E, and a spring, N, serves to retain the relief-regulator L on the plug M. In the example shown in the drawings this spring is made in the form of a disk, Fig. 11, and it bears

against a shoulder, n , formed in the interior of the supply-chamber. The plug M is bored out to form the measuring-chamber O , and into this measuring-chamber is fitted the plunger P , which is secured in the inner end of the rod E by means of a pin, o , the connection between the plunger and the rod being of such a nature that the plunger has sufficient freedom to accommodate itself to such disturbances in the position of the rod E , which may be caused by the inequalities of the packing in the stuffing-box, and which, without the hinge-connection between the stuffing-box and the valve-seat, would be liable to cause the plunger to bind in the measuring-chamber. In the relief-regulator L is formed a circular-channel, l' , which is closed at the outside by a sieve, l , Figs. 3, 6, and 12, and which, through the openings in said sieve, 20 communicates with the supply-chamber B . From the circular channel l' extends a groove, l^2 , to the end of the relief-regulator next the movable head C . The plug M is provided with two or more holes, m' , Figs. 3 and 6, which 25 communicate with the circular-channel l' in the relief-regulator L , and through which the measuring-chamber O is brought into communication with the supply-chamber B . In the plug M are a series of relief-openings, m^2 m^{21} m^{22} m^{23} m^{24} m^{25} m^{26} m^{27} , which are graduated, or, in other words, so placed that the quantity of oil permitted to flow from the measuring-chamber back into the supply-chamber, is 30 more or less according to the relief-opening 35 which is brought into action.

The outer end of the measuring-chamber O is closed by a valve, Q , which is forced up against its seat q by a spring, R . This spring is, by preference, made in the form of a spider, 40 as shown in Fig. 10, and it acts upon the valve Q by means of a stem, S , which is guided in the barrel D , and which is provided with a foot, s , which fits loosely into a cavity in the valve Q , and the end of which is rounded, so 45 that it allows the valve sufficient freedom of motion to accommodate itself to its seat q .

The stem S is provided with a series of grooves, s^2 , which extend in the direction of its axis, (see Figs. 8 and 9,) so that if the barrel D becomes filled with oil and the stem is moved in and out the oil can escape through said grooves. The stem S is bored out to receive a rod, T , which extends through a stuffing-box, d^2 , and the outer end of which bears 50 against a lever, U , which swings on gudgeons u , Fig. 14, and the upper end of which carries the clapper V , which is intended to act upon the bell W . The lower end of the lever U is exposed to the action of a spring, v , which 60 has a tendency to throw the clapper V back away from the bell W .

From the foregoing description it will be seen that the valve Q is seated in the end of the measuring-chamber and that the plunger P moves forward close to the valve, so that the same is enabled to force all the oil which has entered the measuring-chamber at the back-

stroke out of said chamber at its forward stroke; and it will be further seen that when the nut J , Fig. 3, is turned back and the index I is drawn away from the disk G' the rod E can be turned round, and by turning this rod the relief-regulator L is also turned on the plug M . If the rod E is turned so as to bring the index I opposite the hole g^2 in the disk G' , the relief-regulator L is brought into that position in which its longitudinal groove l^2 covers the relief-opening m^2 in the plug M . This is the position represented in Fig. 3. If the plunger P is set in motion, it moves back just beyond the circular groove l' in the relief-regulator L , leaving the oil in the supply-chamber B free to pass into the measuring-chamber O , through the circular groove l' and the openings m' , and to fill up the space in front of the plunger. 80 When the plunger P begins its return-stroke and passes the openings m' in the plug M , all the oil contained in the measuring-chamber O in the space between the openings m' and the valve Q would be forced out through said valve 85 into the delivery-pipe X if it was not for the relief-openings m^2 m^{21} m^{22} m^{23} , &c., in the plug M . But since (in the position shown in Fig. 3) the opening m^2 communicates, through the longitudinal groove l^2 , with the supply-chamber B , all the oil between the front end of the plunger and the relief-opening m^2 will be forced out of the measuring-chamber and only the oil contained in the space between the relief-opening m^2 and the valve Q , which may 90 be termed the effective space of the measuring-chamber, will be forced out into the delivery-pipe. This effective space of the measuring-chamber can be increased or decreased by adjusting the relief-regulator L . If the index I is set to engage the hole g^2 in the disk G' , the longitudinal slot l^2 of the relief-regulator L covers the relief-opening m^2 and the effective space of the measuring-chamber is reduced to a minimum, so that only a drop of 100 oil will be driven out of the same for every stroke of the plunger, while by setting the index so as to engage the hole g^2 in the disk G' the effective space of the measuring-chamber is increased to its maximum. 115

The oil, in being forced out of the measuring-chamber, must necessarily force the valve Q back away from its seat q , and whenever the valve moves back it actuates the lever U through the rod T ; but if the supply of oil has given out, or if from some other cause no oil is driven out of the measuring-chamber by the plunger P , the lever U remains stationary. By these means this lever becomes a visible or (if it is provided with a clapper) an audible 125 signal, which indicates the correct action of the lubricator.

As already stated, the relief-regulator L , as represented in Figs. 3, 6, and 12, has the form of a shell, which is ground upon the plug M , 130 and which is turned in order to bring the different relief-openings into action. Instead of adjusting the relief-regulator by imparting to it a rotary movement, said relief-regulator

can be so constructed that it can be adjusted by imparting to it a rectilinear sliding movement. This construction is illustrated in Fig. 15, in which B represents the supply-chamber. 5 O is the measuring-chamber. Q is the valve of the measuring-chamber. P is the plunger, which works in the measuring-chamber. M is the plug, which is provided with one or more holes, m' , through which oil is admitted 10 from the supply-chamber B to the measuring-chamber whenever the plunger P is drawn back beyond said holes. m^2 m^{21} m^{22} m^{23} are the relief-openings, which extend through the side of the plug M at different distances from the 15 discharge-opening of the measuring-chamber. The plug M is cylindrical, and on it is fitted the relief-regulator L, which is connected to a shaft, L', that has its bearings in the sides of the supply-chamber B, and on which are 20 secured slotted arms l^7 l^8 , which engage with pins l^9 , projecting from the sides of the relief-regulator L. By turning the shaft L' the relief-openings m^2 m^{21} m^{22} m^{23} can be opened or closed. In the position shown in Fig. 15 all the relief- 25 openings are open. If the plunger P is moved back beyond the hole m' , the measuring-chamber O fills with oil, and if the plunger is moved forward toward the valve Q, the oil in front of the plunger will be forced out through the relief-openings until the front end of the plunger has passed the relief-opening m^2 . The oil between this opening and the valve Q is driven out through the valve. If the relief-regulator L is moved to cover the opening m^2 all the oil 30 contained in the measuring-chamber between the opening m^{21} and the valve is driven out through the valve, and so on, as will be readily understood from the foregoing description.

What I claim as new, and desire to secure 35 by Letters Patent, is—

1. The combination, with the supply-chamber and with the delivery pipe or channel, of a plug, M, having a measuring-chamber and the graduated relief-openings, a valve controlling the communication between the measuring-chamber and the delivery-pipe, the plunger working in the measuring-chamber and its relief-regulator, substantially as described.

2. The combination, with the supply-chamber and with the delivery pipe or channel, of a plug, M, having a measuring chamber and the graduated relief-openings, a valve controlling the communication between the measuring-chamber and the delivery-pipe, the plunger working in the measuring-chamber, the relief-regulator, and an index constructed to show the position of the relief-regulator, substantially as described.

3. The combination, with the supply-chamber and with the delivery pipe or channel, of the plug M, having a measuring-chamber and the graduated relief-openings, the valve controlling the communication between the measuring-chamber and the delivery-pipe, the stem S, the rod T, the plunger working in the meas-

uring-chamber, the relief-regulator, and the alarm, substantially as described.

4. The combination, with the supply-chamber and with the delivery pipe or channel, of the plug M, having a measuring chamber and the graduated relief-openings, the valve controlling the communication between the measuring-chamber and the delivery-pipe, the plunger P working in the measuring-chamber, the relief-regulator fitted upon the plug M, the rod E, which carries the plunger P and connections, substantially as herein shown and described, for turning the relief-regulator when the rod E is turned.

5. The combination, with the supply-chamber and with the delivery pipe or channel, of the plug M, having a measuring-chamber and the graduated relief-openings, the valve controlling the communication between the measuring-chamber, and the delivery-pipe, the plunger P, working in the measuring-chamber, the relief-regulator fitted upon the measuring-chamber, and having the grooves l^7 l^8 , and the sieve l^9 , extending round the groove l^7 , substantially as described.

6. The combination, with the supply-chamber and with the delivery pipe or channel, of the tapering plug M, having a measuring-chamber and the graduated relief-openings, the valve controlling the communication between the measuring-chamber and the delivery-pipe, the relief-regulator L, fitted on the tapering plug M, the spring N, acting on the relief-regulator, the plunger P, working in the measuring-chamber, and means, substantially as described, for adjusting the position of the relief-regulator.

7. The combination, with the supply-chamber O and the delivery-pipe X, of the plug M, having the measuring-chamber and the graduated relief-openings, the valve Q, controlling the communication between the measuring-chamber and the delivery-pipe, the relief-regulator L, fitted upon the plug M, the plunger P, the rod E, carrying the plunger, the arm K and pin k , for connecting the rod E with the relief-regulator, the dial-plate G', and the index I, substantially as described.

8. The combination, with the supply-chamber and with the delivery-pipe, of the inclosed measuring-chamber, the plunger working in the inclosed measuring-chamber, the valve controlling the communication between the inclosed measuring-chamber and the delivery-pipe, and an audible or visible signal, as described.

9. The combination, with the supply-chamber and with the delivery-pipe, of the inclosed measuring-chamber, the plunger working in the inclosed measuring-chamber, the valve Q, controlling the communication between the inclosed measuring-chamber and the delivery-pipe, the stem S, the spring R, the pin T, the lever U, the clapper V, and the bell W, substantially as described.

10. The combination, with the supply-chamber

ber and with the delivery-pipe, of the inclosed measuring-chamber, the plunger working in the inclosed measuring-chamber, the valve Q, controlling the communication between the inclosed measuring-chamber and the delivery-pipe, the stem S, detached from the valve and loosely fitting into the same, and the spring R, substantially as described.

11. The combination, with the supply-chamber and with the delivery pipe or channel, of an inclosed measuring-chamber having two or more openings, one being in advance of the other and all communicating with the supply-chamber, a plunger working in the inclosed measuring-chamber, and a valve controlling the communication between the inclosed measuring-chamber and the delivery-pipe, substantially as described.

12. The combination, with the supply-chamber and with the delivery pipe or channel, of an inclosed measuring-chamber having two or more openings, one in advance of the other and communicating with the supply-chamber, a valve-seat formed at the end of the inclosed measuring-chamber, a valve fitting said seat and made to control the communication between the inclosed measuring-chamber and the delivery-pipe, and a plunger made to move in the inclosed measuring-chamber close to the valve, substantially as described.

13. The combination, with the supply-chamber B and with the inclosed measuring-chamber O, of the stuffing-box C, the rod E, extending through this stuffing-box, means, substantially such as herein described, for imparting 35 to the rod a reciprocating motion, the plunger P, made to work in the inclosed measuring-chamber, and the hinge-joint which connects this plunger to the rod E and is situated between the stuffing-box C and the end of the inclosed measuring-chamber, substantially as described.

14. The combination, with the supply-chamber B and the inclosed measuring-chamber O, of the plunger P, made to work in the measuring-chamber, the rod E, connected to the plunger, the cross-head F, carrying the rod E, the driving-shaft G, the eccentrics d d, mounted on this shaft, and the rods e e, connecting these eccentrics with the cross-head F, 45 substantially as described.

In testimony whereof I have hereunto set my hand and seal in the presence of two subscribing witnesses.
